UNITED STATES PATENT OFFICE.

WILLIAM H. ATKINS, OF MILWAUKEE, WISCONSIN.

DESIGN FOR A BOOT.

SPECIFICATION forming part of Design No. 29,751, dated November 29, 1898.

Application filed November 2, 1898. Serial No. 695,326. Term of patent 7 years.

To all whom it may concern:

Be it known that I, WILLIAM H. ATKINS, of Milwaukee, in the county of Milwaukee and State of Wisconsin, have invented and produced a new and original Design for Boots, of which the following is a description, reference being had to the accompanying drawings, which are a part of this specification.

Figure 1 is a perspective view of a boot, showing my new design; and Fig. 2 is a plan view thereof.

As shown in the drawings, the leading or material feature of my design consists of the peculiar shape and configuration of the top surface of the boot at or adjacent to the instep portion thereof, whereby an ornamental design for the boot-front is produced.

The rear edge of the upper A of the boot has projecting centrally therefrom a strip B, which strip extends rearwardly and upwardly along the instep for a desired distance. The lower opposite side edges of this strip are curved inwardly, and the upper opposite side edges are also curved inwardly. The upper ends of the lower curves and the lower ends of the upper curves meet at opposite lateral points C C.

Beneath the strip B is an instep-facing D,

the front edge of which underlapping the rear edge of the upper A, and the side edges of said facing overlapping elastic gores E E. These side edges gradually converge toward the upper or rear edge of the facing, thereby forming a piece of gradually-diminishing width toward its upper edge. 35

The peculiar contour and arrangement of the parts just explained produce an extremely ornamental effect for the boot-front. This ornamental effect is enhanced by the ornate configuration or shape of the strip B 40 in connection with the instep-facing underlying the strip, said strip being thereby made to appear as a raised surface and the instep-facing as a sunken or intaglio surface.

Having described my invention, what I 45 claim as new, and desire to secure by Letters Patent, is—

The design for a boot, as herein shown and described.

In testimony whereof I affix my signature 50 in presence of two witnesses.

WILLIAM H. ATKINS.

Witnesses:

A. L. MORSELL,
ANNA V. FAUST.
